United States Patent Office.

E. H. ASHCROFT, OF LYNN, MASSACHUSETTS.

Letters Patent No. 67,478, dated August 6, 1867.

IMPROVEMENT IN STEAM-CYLINDER LUBRICATORS.

The Schedule referred to in these Letters Patent and making part of the same.

TO ALL WHOM IT MAY CONCERN:

Be it known that I, E. H. ASHCROFT, of Lynn, in the county of Essex, and State of Massachusetts, have invented certain new and useful Improvements in Lubricators for Locomotive Cylinders; and I do hereby declare that the following is a full, clear, and exact description of the same, reference being had to the accompanying drawings, in which—

Figure 1 is an elevation of my improved lubricator.

Figure 2 is a vertical section of the same; and

Figure 3 is a similar view of my lubricator in a modified form, the casing F being removed.

The nature of my invention consists in the construction of a lubricator for locomotive or other steam-cylinders, that the oil or tallow may be fed to the same automatically when there is no steam in the cylinder, as when the locomotive is approaching a station, going down grade, etc., no oil or tallow being required when steam is allowed to enter the cylinder, as it will lubricate the parts.

To enable others to make and use my invention, I will proceed to describe its construction and operation.

In the drawings, A is the cup for containing the oil or tallow, and is provided with a cover, B. C is a tube secured in the cup A, and carries the valve-rod and valve D, which regulate the flow of oil to the cylinder. This tube C is perforated with holes at the top and bottom, the perforations at the bottom serving to allow the lubricating material to enter the tube C, while those at the top are for the purpose of allowing any steam which may enter said tube from the cylinder to escape. E is a valve, which is shut by the pressure of steam when the same is allowed to enter the cylinder, and is opened when the supply is cut off. The space G, shown in fig. 2, formed by the cup A and casing F, is for the purpose of containing steam from the cylinder to melt the tallow in cup A.

The operation is as follows: A requisite quantity of tallow or other lubricating material is put into the cup A, and enters the tube C through the perforations in the bottom of the same. It will then escape through valve D into the chamber immediately underneath, and from there through the valve E into the cylinder. But if there is steam in the cylinder, the pressure of the same will close the valve E, and prevent the lubricating material from escaping.

Having thus described my invention, what I claim as new, and desire to secure by Letters Patent of the United States, is—

1. The combination of valve E, cup A, tube C, and inner valve D, constructed, arranged, and operating in the manner substantially as shown and described, and for the purpose set forth.

2. The combination of said parts with outer cup F, arranged, constructed, and operating in the manner substantially as shown and described, and for the purpose set forth.
